US00D910232S

(12) **United States Design Patent** (10) **Patent No.:** **US D910,232 S**
(45) **Date of Patent:** **** Feb. 9, 2021**

(54) **ELECTRONIC VAPORIZER**

- (71) Applicant: **Altria Client Services LLC**,
Richmond, VA (US)
- (72) Inventor: **Charles P. Kauss**, Atlanta, GA (US)
- (73) Assignee: **Altria Client Services LLC**,
Richmond, VA (US)
- (**) Term: **15 Years**

(21) Appl. No.: **29/681,725**

(22) Filed: **Feb. 27, 2019**

Related U.S. Application Data

(63) Continuation of application No. 29/572,791, filed on
Jul. 29, 2016, now Pat. No. Des. 842,535.

(57) **CLAIM**

The ornamental design for an electronic vaporizer, as shown and described.

DESCRIPTION

FIG. 1 is a perspective front view of an electronic vaporizer. FIG. 2 is a front view of the electronic vaporizer of FIG. 1. FIG. 3 is a rear view of the electronic vaporizer of FIG. 1. FIG. 4 is a right side view of the electronic vaporizer of FIG. 1. FIG. 5 is a left side view of the electronic vaporizer of FIG. 1. FIG. 6 is a top view of the electronic vaporizer FIG. 1; and, FIG. 7 is a bottom view of the electronic vaporizer of FIG. 1. The broken lines in the drawings depict portions of the electronic vaporizer that form no part of the claimed design.

1 Claim, 4 Drawing Sheets
